UNITED STATES PATENT OFFICE

SAMUEL MOORHOUSE, OF LEEDS, ENGLAND

SPINNING MACHINE

Application filed January 19, 1928, Serial No. 247,981, and in Great Britain January 31, 1927.

This invention relates to drag devices for the bobbins of spinning machines known as flyer spinning, doubling, twisting and like frames and consists in the production and application of means whereby the drag or retardation of the bobbins is automatically regulated so that according to the desired speed at which they have to run as regulated by their increasing diameters as the coils of yarn 10 are wound thereon, so will the retardation be adjusted to meet the said requirements and keep the tension or pull on the threads throughout the spinning operations even and regular. That is to say the tension of the 15 yarn at the commencement of the coiling of same upon the empty bobbin is regulated automatically so that it does not disadvantageously vary from said condition throughout the whole of the winding operations until 20 the last coils of yarn are wound upon the bobbins. The devices I employ enable me to adjust same so that at the commencement of the spinning and winding operations I can have a greater or less tension as occasion may 25 require while said tension may be automatically increased as the increasing diameter of the coils on the bobbins necessitate.

In the accompanying sheets of drawings:—

Fig. 1 is a sectional elevation of the lifter plate and spindle with one of my improved magnetic drag devices mounted thereon, said devices being also shown in section.

Fig. 2 is a plan of the parts shown by Fig. 1 with the bobbin removed.

Fig. 3 is a sectional plan taken on line 3—3 of Fig. 1. The devices shown by said Figures 2 and 3 are drawn approximately full size.

Fig. 4 is a plan showing a modification using two electromagnets for each bobbin as hereinbefore described.

Fig. 5 is an end elevation of the end frame of a spinning and like machine, a part of which is cut away to show the lifter plate 45 with parts connected thereto as is herein-after explained.

Fig. 6 is a front elevation to a larger scale showing certain of the parts adjoining the lifter rail illustrated by Fig. 5.

Fig. 7 is an elevation (partly in section)

showing the lower flange of a bobbin mounted upon a metal support hereinafter described.

In carrying my invention into effect I make use of an electro-magnet for each spindle *b* 55 which carries the flyer *b'* and this magnet according to one arrangement as shown by Fig. 4 is so formed that one pole piece *a*¹ is on one side of the spindle *b* while another pole piece *a*² is on the other side of said spindle with non-magnetic metal pieces *c*, *c'* occupying the spaces between said pole pieces *a*¹ and *a*² in order to form a continuous surface upon and over which the base *d*¹ of the bobbin 60 *d* may rest and revolve.

The base *d*¹ (see Fig. 1) of the bobbin *d* has secured to it a plate *f* of iron or steel and this is secured by screws or otherwise to said base *d*¹ or it may be arranged to rest loosely upon the magnet in which case the 70 bobbin will have grooves *d*² in it to allow the projections *f*¹ and *f*² (Fig. 7) to take into same in well known manner, thus while the actions of the electromagnet upon the plate *f* are such as to retard its rotation the 75 screws securing said plate *f* to the bobbin *d* also secure retardation of said bobbin while when the bobbin is placed loosely with the grooves in its base spanning the projections *f*¹ and *f*² then the retardation of the plate 80 *f* has also the effect of retarding the bobbin *d*. The said plate *f* rests upon the pole pieces *a*¹ and *a*² or is retained above same sufficiently as to be clear thereof but still remain under the magnetic influence of said pole pieces. 85

Instead of making use of the pole pieces *a*¹ and *a*² I find that the central part *a*³ of the member *a*⁴ shown by Figs. 1, 2 and 3 acts efficiently and this member I arrange to be surrounded by the coils of wire *g* which 90 energize the central part *a*³ as will be understood, thus when the current passes through said coil *g* the central part *a*³ of the member *a*⁴ is magnetized and acts upon the plate *f* in desired manner.

In the former arrangement as shown by Fig. 4 where I have two pole pieces *a*¹ and *a*² and two separate coils *g*² and *g*³, I may arrange said coils *g*² and *g*³ to be connected in series, the coils *g*² forming one series while 100

the coils g^3 form the other series in order that the current sent through same will energize the two series of pole pieces a^1 and a^2 as desired.

In the arrangement shown by Figs. 1, 2 and 3 the member a^4 is formed so that in the annular space 2 the insulated coils of wire g may be placed in such a manner that one end 3 of the coils of wire g may be in contact with the lifter plate h while the other end 3^a will be in contact with a strip of copper or like good conducting metal k which is mounted upon and insulated from said lifter plate h . The coils g are insulated from the member a^4 so that when the current is passed through same by passing through the strip of copper k , the circuit is completed by the said current earthing through the lifter plate h .

As means for regulating or adjusting each magnet a so that it will act as desired, or to the required extent upon its respective bobbin d , I arrange the upper surface m^1 of an annular member m to form the surface for actual contact with and the support for the plate f and its bobbin d , thus by having said annular member m of steel with its upper surface m^1 hardened I secure a desired form of surface upon which the plate f may revolve. By having the said annular member m screw threaded at m^2 in order to take over the part a^5 of the member a^4 I am enabled to rotate said member m and cause it to rise or descend over the part a^5 and therefore to raise the plate f slightly above the upper surface of the magnet a^3 or to lower same into actual contact therewith if necessary, thus the drag on each bobbin, or the actions of the electromagnet thereon through the plate f , may be adjusted at the commencement of the spinning operations.

When it is desired to have said drag automatically varied, as when spinning cops or upon bobbins where the shoulder part tapers down to a nose part of the cop as shown by Fig. 6 then I may have a varying rheostat p so that the strength of the current is decreased as the nose of the cop is approached in well known manner, while it is increased when coils of yarn are being wound on the shoulder parts of said cops. In this arrangement of devices the rising and falling of the lifter plate h carries the contact piece h^1 over the terminals of the rheostat p and this rheostat p is raised and adjusted by the upper end of the contact piece h^1 rising and falling with the lifter plate. Said lifter plate h also acts upon projections p^2 and p^3 so as to adjust same in a higher or lower position as the building of the cop proceeds.

As means for regulating or retaining the annular member m in any position on which it may have been adjusted a spring actuated sphere or ball s which is carried by the handle s^1 is caused to enter the notches m^4 made in the member a^4 as shown by Fig. 3

while if the member m is desired to be retained in position without being interfered with by said adjusting sphere or ball s then the member m may be turned so that the blank part m^5 is opposite the said ball s .

The electric current, as is before stated, may be obtained from any suitable source of supply and this may be controlled through a switch w mounted upon the framework at the end of the machine in such a position as to be accessible to the attendant. In this case the current is arranged to pass through the switch w , through the volt meter x , through the rheostat y and cable y^1 to the strip k on the lifter plate h . By the employment of these devices the current may be increased or decreased in strength as will be understood so that the drag requirements of any particular kind of thread or fibre may be provided for by the rheostat y .

Such being the nature and object of my said invention what I claim is:—

1. In drag devices for flyer spinning, doubling, twisting and like machines, a spindle, a flyer, means for rotating said flyer, a plate through which said spindle extends, an electromagnet mounted on said plate, means for energizing said electromagnet, a bobbin, a metal disc forming the drag member arranged to be fixed to said bobbin above the electromagnet.

2. In drag devices for flyer spinning, doubling, twisting and like machines, a spindle, a flyer, means for rotating said flyer, a plate through which said spindle extends, a circular electromagnet mounted on said plate, means for energizing said electromagnet, a bobbin and a metal disc forming the drag member arranged above said electromagnet and to be detachably secured to the bobbin.

3. In drag devices for flyer spinning, doubling, twisting and like machines, a spindle, a flyer, means for rotating said flyer, a plate through which said spindle extends, an electromagnet mounted on said plate, means for controlling the electric current supplied to said electromagnet, a bobbin, a retarding surface, a metal drag member rotatable with the bobbin and arranged to be moved into contact with said retarding surface when the magnet is energized, and means for automatically increasing and decreasing the drag when the thread is being wound upon the shoulder of a cop and on the nose of the cop.

4. In drag devices for flyer spinning, doubling, twisting and like machines, a plurality of spindles and flyers, means for rotating said flyers, a plate through which the series of spindles extends, an electromagnet on said plate for each spindle, means for supplying an electric current to said electromagnets, adjusting means whereby said current may be regulated to act equally on all of the elec-

tromagnets, a metal drag member for each spindle each of said drag members being arranged upon its controlling electromagnet and a bobbin or like member mounted upon each of said drag members so as to rotate therewith.

5. In drag devices for flyer spinning, doubling, twisting and like machines, a plurality of spindles and flyers, means for rotating said flyers, a plate through which said spindles extend, electromagnets mounted on said plate, devices for supplying an electric current to so as to energize the electromagnets, a rheostat for controlling said current, metal drag members above and operating in conjunction with the electromagnets and bobbins mounted upon the metal drag member so as to rotate with them.

6. In drag devices for spinning machines, the combination of a spindle, a flyer, means for rotating the flyer, a plate through which the spindle extends, an electromagnet mounted on said plate, means for energizing the magnet, a member provided with a retarding surface, a rotatable bobbin, and a metal drag member rotatable with the bobbin and arranged to be attracted by the magnet into contact with said retarding surface.

7. In drag devices for spinning machines, the combination of a spindle, a flyer, means for rotating the flyer, a plate through which the spindle extends, an electro-magnet mounted on said plate and including a plurality of coils, means for energizing said magnet, a member provided with a retarding surface, a rotatable bobbin, and a metal drag member arranged above the electro-magnet and rotatable with the bobbin, the drag member being attracted into contact with said retarding surface when the magnet is energized.

8. In drag devices for spinning machines, the combination of a spindle, a flyer, means for rotating the flyer, a plate through which the spindle extends, an electro-magnet mounted on said plate, means for energizing said magnet, a member provided with a retarding surface, a rotatable bobbin, a metal drag member rotatable with the bobbin and arranged above and adapted to be attracted by the magnet into contact with said retarding surface when the magnet is energized, and means for varying the action of the magnet on the drag member.

9. In drag devices for spinning machines, the combination of a spindle, a flyer, means for rotating the flyer, a plate through which the spindle extends, an electro-magnet mounted on said plate, means for energizing the magnet, means for automatically controlling the electric current supplied to the magnet, a member provided with a retarding surface, a rotatable bobbin, and a metal drag member rotatable with the bobbin and arranged above the magnet and adapted to be

moved into contact with said retarding surface when the magnet is energized.

10. In drag devices for spinning machines, the combination of a spindle, a flyer, means for rotating the flyer, a plate through which the spindle extends, an electromagnet on said plate, means for energizing the magnet, a member provided with a retarding surface, a rotatable bobbin, and a metal drag member rotatable with the bobbin and positioned between the bobbin and magnet and adapted to be attracted into contact with said retarding surface when the magnet is energized.

11. In drag devices for spinning machines, the combination of a spindle, a flyer, means for rotating the flyer, a plate through which the spindle extends, an electromagnet on said plate, means for energizing the magnet, a rotatable bobbin, a member provided with a retarding surface, a metal drag member rotating with the bobbin and arranged above the magnet to be attracted thereby into contact with said retarding surface, an adjustable member for varying the action of the magnet on the drag member, and means for retaining said adjustable member in any desired position.
